4 Sheets-Sheet 4

UNITED STATES PATENT OFFICE.

GUS F. LENK, OF DALLAS, TEXAS.

INCINERATOR.

Application filed August 1, 1924. Serial No. 729,653.

To all whom it may concern:

Be it known that I, GUS F. LENK, citizen of the United States of America, residing at Dallas, in the county of Dallas and State of Texas, have invented certain new and useful Improvements in Incinerators, of which the following is a specification.

This invention relates to new and useful improvements in incinerators.

10 The object of the invention is to provide an improved type of incinerator highly efficient in cremating or incinerating carcasses, wet and dry garbage and other offal and by its arrangement and operation eliminating all odors, obnoxious and objectionable gases and smoke.

Another important object of the invention is to provide an incinerator capable of handling the general run of city or town 20 garbage, trash, refuse or excrement, without becoming a nuisance or a detriment to a community or locality.

A particular object of the invention is to provide a drying and preheating table within 25 the main chamber of the furnace, upon which the offal is dumped, whereby wet matter is drained and given a preliminary drying; whereby liquids are collected and evaporated; and whereby the charge is made 30 more combustible and consumable.

Another object is to utilize the waste heat to heat said table and thus not only make for economy, but to extract from the waste gases, heat units which would otherwise 35 escape through the smoke stack.

A still further object is to provide baffle or division walls in the main chamber of the furnace extending from the front wall to the table and between which baffle walls the 40 grates are located; whereby the flames are caused to pass over and under the matter being burned and to whip around the ends of said walls and concentrate at a single outlet or escape duct at one side of the furnace.

An advantage of such a furnace is that it can be built shallow from front to rear and elongated from side to side, thus permitting the use of shorter stoking tools and 50 requiring less stoking room.

A very important feature of the invention is the provision of a tunnel or passage under the evaporating table connecting at one end with a super-combustion chamber 55 and connected at the other end with a smoke stack, together with a grill at the

former end for restricting the passage of unconsumed matter and acting to spread and agitate unconsumed gases and odors; said tunnel not only heating the evaporating 60 table, but absorbing heat units from the otherwise waste products of combustion.

Another object of the invention is to provide a trough along the lower front edge of the drying table in which liquids will be 65 collected and evaporated and prevented from passing to the grates and ash pits.

A construction designed to carry out the invention will be hereinafter described together with other features of the invention. 70

The invention will be more readily understood from a reading of the following specification and by reference to the accompanying drawings, in which an example of the invention is shown, and wherein: 75

Fig. 1 is a front elevation of an incinerator constructed in accordance with my invention.

Fig. 2 is a horizontal cross-sectional view of the same above the floor line, 80

Fig. 3 is a horizontal cross-sectional view on the line 3—3 of Fig. 5,

Fig. 4 is a longitudinal vertical sectional view on the line 4—4 of Fig. 5,

Fig. 5 is an enlarged transverse vertical 85 sectional view on the line 5—5 of Fig. 1,

Fig. 6 is an enlarged sectional view of one of the charging hoppers,

Fig. 7 is a detail of one of the roof block units of the burning chamber, and 90

Fig. 8 is a sectional view of a portion of said roof.

In the drawings the numeral 10 designates a base upon which a front wall 11, an end wall 12, a rear wall 13 and an end 14 are 95 erected. These walls and the base are suitably constructed in accordance with incinerator engineering. The rectangular structure formed by these parts is comparatively shallow from front to rear in proportion to its length between the end walls. This is an important feature as it permits all parts of the interior to be reached through openings in the front wall, with a short handle rake and thus cuts down the stoking room 100 usually required in front of the incinerator.

A floor 15 is supported at the upper ends of the wall and is composed of a concrete mixture reinforced by I-beams 16 extending at right angles to each other and having 110 their ends supported in the walls. The incinerator is charged from the floor. A ver-

tical division wall 17 adjacent the wall 14 divides the interior of the incinerator, the greater portion, about four-fifths more or less, lying to the right (Figs. 3 and 4) and 5 constituting a main or burning chamber. I provide a floating or detached roof or arch for this chamber composed of fire resisting blocks or tile 18, suspended from clamps 19 (Fig. 7) supported by eye bolts 20 de- 10 pending from hangers 21 clamped to the beams 16. These blocks may assume a de- sired form and while fitting together are not tied to the walls of the furnace, thus allowing for expansion and contraction and 15 permitting ready removal and replacing.

Over the rear portion of the chamber the roof is horizontal, but is inclined down- 20 wardly over the front portion thereof. By using square blocks uniformity is had, and 25 rectangular charging hoppers 22 may be used. The hoppers have their upper ends flanged and countersunk in the floor 15. Each hopper has a vertical collar 23 secured to its lower end and surrounded by the 30 blocks 18 of the roof. The details of the hopper form the subject matter of a co- pending application filed August 1, 1924, Ser. No. 729,650. In each collar is hinged 35 a cover composed of a fire resisting tile 24 secured in a back 25. The tile rests upon an interior flange 23' at the bottom of the collar. From the front end of each cover a flexible connection 26 extends upward and passes behind a pulley 27 on the rear wall 35 of the building. By this means the cover may be swung upward in a convenient manner.

The hoppers have their greatest length 40 directed forwardly as is shown in Fig. 2 and are located near the rear wall 13. Within the burning chamber and under the hoppers is an evaporating and drying table 28 inclined downwardly from the rear wall and having its front end supported above 45 the base 10 on a vertical wall 29. The table is suitably formed of fire resisting ma- 50 terial and may be made in sections or blocks so as to be replaced. This elevated table has a longitudinal sump or trough 30 along 55 its front edge for catching and retaining the liquids, whereby the latter are evapo- 60 rated and prevented from flowing down into the ash pits. This table is arched over a flue or tunnel 32 extending parallel to the 65 rear wall 13 and behind the wall 29. The bottom of the tunnel is formed by the base 10. As will be hereinafter explained the hot gases and air currents escaping from the 70 burning chamber pass through said tunnel, thus heating the table from the underside.

The burning chamber is divided by trans- 75 verse vertical baffle walls 33 extending from the base 10 to the roof and from the front 80 wall 11 to the wall 29 and the front edge

of the table. Between the walls 33 and on each side thereof, are fire grates 34 of any suitable type. These grates are supported by the walls 11, 12, 17, 29 and 33 above the base 10 and about midway the height of the 70 front of the table 28. Ash pits 35 are formed below the fire grates and access is had thereto through doors 36 in the front wall 11.

Above the grates 34 are suspension grates 75 37 located in a plane approximately flush to the front edge of the table, but subject to variation. These grates are of the water circulating type and form the subject matter of a copending application filed August 80 1, 1924, Ser. No. 729,652. The suspension grates are much more open than the fire grates and have spaces for small articles and pieces to drop through. The purpose of the suspension grates is to elevate above 85 the main fire, carcasses, and other slow burning matter, whereby it will be partially consumed and disintegrated before drop- 90 ping through to the fire grates. Doors 38 in the front wall 11 give access to the 95 spaces between the grates 34 and 37. Above the grates 37 inwardly flared (Figs. 3 and 5) liners 39 are mounted in doorways in the front walls and are closed by doors 40. By means of the flared openings the grates may 95 be more freely stoked and this same structure may be adopted in connection with the doors 36 and 38.

Each baffle wall has a central opening 41 extending from a point between the grates 100 34 and 37 to the roof of the burning chamber. A similar but larger opening 42 is provided in the wall 17 for the escape of the products. It will be seen that the air currents and flames will pass through the 105 openings 41 in the baffle walls above the grates 34 and above and below the grates 37, thus thoroughly igniting and burning the matter deposited on said grates. The flames and currents will also whip around 110 the rear ends of the baffle walls and pass over the table 28. The flames, currents and gases will be drawn toward the opening 42 and at this point the fire will be most in- 115 tense, providing a cut-off fire through which 115 all products must pass.

It is to be understood that the suspension grates might be omitted and matter per- 120 mitted to drop upon the fire grates 34 from the table. It is also possible to construct the furnace without the baffle walls 33. The long shallow burning chamber is of partic- 125 ular advantage as it is more easily stoked and permits a quicker spreading of the charge. The drying table is very essential 125 in burning wet and slow burning matter.

Between the division wall 17 and the end wall 14 I form an intensifying chamber 43 and a combustion chamber 44, through 130 which the products escaping from the open-

ing 42, pass to the tunnel 32. These chambers form the subject matter of a co-pending application filed Aug. 1, 1924, Ser. No. 729,651. The base 10 forms the floors of these latter chambers and is below the opening 42. The chamber 43 is at the front of the incinerator and is separated from the chamber 44 by a partition 45 extending from the base 10 to the arched roof 46 between the walls 14 and 17. The partition has an arched opening 47. Access through to the chamber 43 is had by doors 48 and 49 in the front wall, matter being introduced through the upper door 49 and ashes removed through the lower door 48.

It is proposed to introduce tin cans and other non-combustible matter raked from the grates 34, into the chamber 43. This matter will become intensely hot and intensify the fire, so that gases passing through the opening 42 will be consumed. The roof being higher than the opening 42 and the arched opening 47, will cause a whirling action in the chamber 43, whereby combustion will be promoted and odors dissipated.

The currents and gases passing through the opening 47 enter the combustion chamber 44. This chamber is supplied with fresh air by a duct 50 extending through the front wall 11 and the end wall 14 and discharging into said chamber. If the gases and currents are not completely cremated when reaching the chamber 44, the injection of oxygen from the duct 50 will tend to complete the combustion of the gases and elimination of odors. An opening 51 provides an entrance to the tunnel 32 and a grille 52 is placed in this opening. The currents and gases after circulating in the chamber 44 are drawn down through the grille into the tunnel.

The grille serves not only to prevent the passage of unconsumed matter into the tunnel, but also acts to spread and agitate any smoke, odors or gases which may pass therethrough. The hot currents passing through the tunnel under the table 28 will adequately heat the same. Also any products escaping into the tunnel will be subjected to a final combustion, so that any odors escaping from the chamber 44 are given final treatment in the tunnel.

Ducts 53 entering the end wall 12 terminate at the tunnel and the currents from the tunnel pass through these ducts. The ducts have their opposite ends entering a detached smoke stack 54 of suitable construction. It is within the scope of the invention to have the tunnel discharge directly into the stack and thus eliminate the ducts. These ducts form part of a forced draft system which is more fully set forth in a co-pending application filed Aug. 1, 1924, Ser. No. 729,649. As natural draft may be supplied through the doors 36, the forced draft is an optional equipment.

The forced draft equipment comprises a suction fan 55 driven by a motor 56 and located adjacent the ducts. The fan will draw air from between the ducts. Such air will be heated by the ducts, so that pre-heated air is employed. The air is discharged from the fan, under pressure, into an elbow 57 which delivers it to a manifold pipe 58 countersunk in the base 10 and extending through the ash pits. Risers 59 extend upwardly in each ash pit from the pipe 58 and terminate in nozzles 60 directed under the grates 34.

In operating the incinerator a fire is first started on the grates 34 in any suitable manner. Incinerators of this type are usually built in houses and an approach (not shown) leads up to the floor 15. The truck or wagon is driven onto the floor 15 and after the tiles 24 are swung upward by means of the connections 26 to open the hoppers 22, the charge of the garbage and trash is dumped and pushed through the said hoppers into the incinerator.

The incinerator having become hot by the products of combustion passing through tunnel 32, whereby the table 28 is heated, the garbage falling upon said table, will be dried. The liquid in the garbage will collect in the trough 31, whereby it will be evaporated. Owing to the inclination of the table the garbage will slide down the same, or it may be raked onto the suspension grates 37. The flaring liners 39 will permit the rake to be easily placed at any desired point. These grates 37 being widely spaced will permit the small pieces to fall through, but larger material, such as carcasses, large rags, etc., will be held in suspension and may be scattered so as to be further dried and more readily consumed. The fire burning in the grates 34 and the material ignited on the grates 37, as well as the table 28, makes for efficient burning. Natural draft may be supplied through the doors 36 or forced draft from the nozzle 60.

The flames and gases will pass through the openings 41 in the baffle walls 33 and will whip around the rear ends of said baffle walls of the table 28. The opening 42 in the division wall 17 provides for a draft which pulls the flames of the fire toward said opening where they concentrate. All gases, odors and smoke must pass through the concentrated flames at the outlet 42. A very high temperature is maintained in the main burning chamber and practically all of the volatile matter will be consumed therein.

However the air currents passing from the main chamber through the opening 42 will reach a higher temperature in the super-heating chamber 43. To maintain this high temperature in said chamber, non-combustible matter, such as tin cans and other kind

of metal after being raked from the grates 34 and 37 are introduced in the chamber 43 through the door 49. Such matter will absorb and hold the heat from the flames entering through the opening 42. This matter will become oxidized and crumble to ashes. Should any odors, smoke or gases not be consumed in passing through the fire at the opening 42, such will be subjected to combustion in the chamber 43. The currents will rise to the arched top 46 of this chamber and be whirled before passing through the opening 47.

The chamber 44 is supplied with fresh air through the duct 50 and the oxygen thus fed into this combustion chamber will assist in causing a complete combustion of products passing through the opening 47. Any unconsumed matter entering the chamber 44 will be arrested by the grille 52 which will also scatter and agitate the odors and gases entering the tunnel 32. The stack 54 will create a draft through the ducts 53 and the tunnel where the products will be accelerated. The products passing through the tunnel will thoroughly heat the table 28 and in so passing will be deprived of any odors which may have escaped from the chamber 44.

The evaporating table and tunnel are the essential features of this invention and make for the success of the incinerator. The currents passing through the tunnel will have a very high temperature and the table 28 will be heated to a very high degree so that wet garbage upon striking the table will be quickly dried and liquid collected in the trough 31 will be very rapidly evaporated. While the suspension grates 37 might be eliminated they prevent the packing of slow burning material on the grates 34 and also give the advantage of a top fire and under fire which has been found to be very efficient.

Various changes in the size and shape of the different parts, as well as modifications and alterations may be made within the scope of the appended claims.

What I claim, is:

1. In an incinerator, the combination of a main burning chamber having a charging hole in its roof, an elevated inclined drying table contiguous to the rear wall of the chamber and having a liquid evaporating trough along its front edge, baffle walls in said chamber extending from the front walls to the table, grates mounted between said baffle walls in front of said table, the chamber having doors in the front walls above and below said grates, and a tunnel outside of the chamber extending under said table and connected with said chamber.

2. In an incinerator, the combination of a main burning chamber having a roof with a charging hole therein, an inclined drying table along the rear wall of the chamber under the charging hole, the table having its front edge extending longitudinally of the central portion of the chamber, a liquid collecting trough contiguous to the front edge of the table, baffle walls in the chamber extending from the front edge of the table to the front wall of said chamber, grates in the spaces between the baffle walls and also between the baffle walls and the sides of the chamber, the chamber having its sole draft outlet in one of the side walls, and a tunnel extending longitudinally under the drying table free from communication with the burning chamber except through the said outlet thereof.

3. In an incinerator, the combination of a main burning chamber having a charging hole in its roof, an elevated inclined drying table contiguous to the rear wall of the chamber and having a liquid evaporating trough along its front edge, baffle walls in said chamber extending from the front walls to the table, grates mounted between said baffle walls in front of said table, and a tunnel outside of the chamber extending under said table and connected with said chamber.

In testimony whereof I affix my signature.

GUS F. LENK.
